UNITED STATES PATENT OFFICE.

THOMAS NASH, OF KAMLOOPS, BRITISH COLUMBIA, CANADA.

DISK SHARPENER.

1,420,568.

Specification of Letters Patent. Patented June 20, 1922.

Application filed February 14, 1921. Serial No. 444,942.

To all whom it may concern:

Be it known that I, THOMAS NASH, a subject of the King of Great Britain, and a resident of the town of Kamloops, in the 5 Province of British Columbia, Canada, have invented certain new and useful Improvements in Disk Sharpeners, of which the following is a specification.

My invention relates to improvements in 10 disk sharpeners, with particular reference to a device for sharpening the disks of disk harrows, and the object of my invention is to provide a sharpener adapted to be attached to the harrow frame and against 15 which the disk may be rotated to be sharpened, and which is strong, simple, and highly practical.

I attain this object by the construction 20 illustrated in the accompanying drawings in which—

Fig. 1 is a side view of my device.

Fig. 2 is a plan view.

Fig. 3 is a front end view.

Fig. 4 is a view illustrating the practical 25 application of the invention.

Similar figures of reference indicate similar parts throughout the several views.

The device is formed preferably as shown 30 in Figs. 1 and 2, and consists of a hard steel plate 1 terminating at one end in a clamp 2 by means of which it may be clamped to the cleaner bar 3 of the harrow, a bolt 4 and a thumb nut 5 being provided for the purpose of tightening the clamp when the device is assembled in place. The plate 1 is 35 twisted as at 6 and inclined with relation to the clamp portion, the angle of inclination and amount of twist being that required to position the plate in proper disk grinding 40 position, as indicated in Figs. 3 and 4. Secured by one end to the plate 1 on its underside is a plate 7 of spring steel, provided on its underside with a box 12 having its opposite sides 13 and 14 inclined inwardly and 45 its forward end and the bottom open adapted to detachably receive an emery stone 15 of the same shape as the box, but of greater depth so that its lower face will project out of the box, as shown in Figs. 1 and 2, when 50 placed therein, the stone being then maintained in place by a spring arm 16 secured by one end to the plate 7, its free end extending adjacent the forward end of the stone to bear against the same.

55 17 indicates the disks of the harrow, 18 an aligning bar passed through the clamp

portions 2 when a number of disks are used, 19 a portion of the harrow frame, while 20 indicates a rod extending between the respective plates 1 and spring plates 7 having 60 secured thereon centrally of and above each plate 7 cams 21 adapted to force the plates downwardly when the rod 20 is turned by means of a lever 22 secured to one end of it, this lever being controlled by a suitable 65 hand operated rod 23 led to any convenient part of the machine within easy reach of the operator.

The manner in which my device is operated will be apparent, it being understood 70 that there are as many of the devices just described clamped to the cleaner bar as there are disks, being held in alignment with each other by means of the aligning bar 18, so that the respective emery stones will bear 75 on the respective disks at the cutting edges, being held thereon against lifting by any suitable means, if desired, when, by moving the harrow to rotate the axle, and operating the cams to depress the plates 7 to carry the 80 stones against the disks, the disks will be rotated against the emery stones and sharpened thereby.

From the foregoing it will be seen that I have provided a disk sharpening device 85 which is simple in construction, cheap to manufacture, easy to install and operate, and which is useful and convenient.

What I claim as my invention is:—

1. A harrow disk sharpener comprising a 90 plate provided at one end with a clamp whereby it may be secured to the harrow frame, a spring arm secured at one end to said plate on its underside, a grinding stone detachably mounted on the underside of said 95 arm, and a cam mounted between said plate and said spring arm the operation of which depresses said arm.

2. A sharpener for rotatable cutters such as harrow disks, which comprise a sharpening element, yieldable supporting means normally holding said sharpening element out of contact with the cutter to be sharpened thereby and a rotatable cam engageable with the sharpening element to force the same 105 into contact with the cutter against resistance of said supporting means.

3. A harrow disk sharpener comprising a plurality of spring plates, each secured to the harrow frame adjacent one of the disk, 110 a sharpening element carried by each plate normally held out of contact with the disk

adjacent thereto, and a shaft carrying a plurality of cam members engageable with said plates to force the sharpening elements into contact with the disks and means actuating 5 said shafts.

4. A harrow disk sharpener comprising a supporting member adapted to be attached to a harrow frame adjacent one of the disks, a box secured to the lower side of the supporting member, said box being open at its 10

bottom and at one end, a grinding stone engaged in the box and removable therefrom through the open end of the box, said stone projecting from the bottom of the box and a member carried by the plate yieldably engaging said stone at the open end of the box to hold the stone into position. 15

Dated at Kamloops, B. C., this 27th day of January 1921.

THOMAS NASH.
